DESIGN FOR A COMBINED BOTTLE AND STOPPER

Henry A. Markus, Chicago, Ill., assignor to California Wine Company, a corporation of Illinois

Application March 28, 1940, Serial No. 91,296

Term of patent 14 years

To all whom it may concern:

Be it known that I, Henry A. Markus, a citizen of the United States, residing in Chicago, in the county of Cook and State of Illinois, have invented a new, original, and ornamental Design for a Combined Bottle and Stopper, of which the following is a specification, reference being had to the accompanying drawing, forming a part thereof.

In the drawing,

Fig. 1 is a side elevational view of said combined bottle and stopper showing my new design;
Fig. 2 is an end elevational view thereof;
Fig. 3 is a side elevational view of the stopper removed from the bottle.

I claim:

The ornamental design for a combined bottle and stopper, as shown.

HENRY A. MARKUS.
